JOHN B. MACNEILL, OF WILKINSBURG, PENNSYLVANIA, ASSIGNOR TO WESTINGHOUSE ELECTRIC & MANUFACTURING COMPANY, A CORPORATION OF PENNSYLVANIA

CIRCUIT BREAKER

Application filed November 6, 1928. Serial No. 317,499.

My invention relates to circuit interrupters and particularly to the contact members therefore.

Difficulty is experienced in closing a circuit interrupter when a short-circuit current is present in the system because of a magnetic force developed in the vicinity of the contacts which opposes the closing force of the operating mechanism and, when the 10 distance to be travelled by the moving contacts, before they fully engage the stationary contacts, is large, this force may rise to a value sufficient to overcome the closing force and prevent the moving contacts from 15 reaching completely engaging positions. This distance that the movable contacts must travel before they are in completely engaging position varies according to the amount of lead the arcing contact is given 20 over the main contact which is regulated by the amount of current and voltage to be interrupted.

It is one object of my invention to provide 25 arcing contacts for a circuit interrupter that shall be positioned a short distance in advance of the main contacts, when in completely disengaged position, and that shall travel a distance considerably in advance thereof when the circuit interrupter is being opened.

Another object of my invention is to provide 30 a circuit interrupter with arcing contacts of the above-described type that shall be moved, to follow the cooperating movable contact member, by a force developed 35 in a current path associated with the said arcing contact.

A further object of my invention is to provide 40 a circuit interrupter with contacts of the above-described type that shall remain in engagement for a period that varies directly with the amount of current flowing in the system at the time of interruption.

45 My invention will now be described in detail, reference being had to the drawings, in which;

Figure 1 is a view, in elevation, of a particular embodiment of my invention in 50 closed position;

Fig. 2 is a view, in elevation, of the embodiment of my invention shown in Fig. 1, with the contacts separated.

My invention comprises, in general, a lift rod 1 supporting a cross bar 2 that has a main current-carrying contact 3 and an arc- 55 ing contact 4 on each end thereof.

In the figures, the right-hand portion of the cross bar 2 is omitted, the contacts thereof being like the left-hand contacts that 60 appear in the figures.

The main contact 3 is laminated and so disposed that the ends of the laminations engage the face of a main stationary contact 5 that is supported on an insulator 6 and has an arm 7 projecting therefrom upon which is pivoted a movable contact member 8 by means of a pin 9. A double-acting spring 11 is mounted upon the pin 9 and its ends are hooked over the arm 7 in such manner that a pin 12 on an arm of the arcing contact member 8 is biased thereby to neutral position, as shown in Fig. 2.

The respective ends of a flexible conductor 13 are fastened to the arm 7 and to the contact member 8 by screws 14 to constitute a loop or short circuit for the current transferred thereto when the contacts 3 and 5 are separated. The magnetic flux about the loop circuit provides a repellent force that 75 causes the contact member 8 to move in a clockwise direction about the pin 9 to a position substantially as shown in dotted lines in Fig. 1.

Such an arrangement causes the arcing 85 contact member 8 to follow the arcing tip 4 a considerable distance beyond its neutral position and, as the amount of travel is proportional to the repellent force set up in the loop, it will be seen that this downward movement will be proportional to the amount of current flowing therein.

During this movement, the pin 12 has moved the bottom arm of spring 11 away from the arm 7 so that, after the current is 90 finally broken and the repellent force no longer acts the spring 11 will bias the pin 12 to cause the contact member 8 to return to its neutral position.

When the circuit interrupter is being 95

closed, the contact 4 will first complete the circuit against the contact member 8 and move it in a counter-clockwise direction until the main contacts are in completely engaged position, which is that shown in Fig. 1. In this position, the pin 12 has moved the top arm of the spring 11 away from arm 7 to thereby apply a biasing force to the contact member 8 when the breaker is tripped, that will turn it in a clockwise direction until the current has been transferred to the loop circuit 13, which will thereafter cause the contact to continue to move until the circuit is completely broken. It will thus be seen that I have provided contact members for a circuit interrupter, including a pair of arcing contacts that are held in engagement during the opening movement thereof over a considerably greater distance than the distance through which they are engaged during the closing movement.

Such an arrangement provides a very short lead of the arcing contact beyond the engaged position of the main contact, so that the circuit interrupter will be closed before a force, such as that set up by a short-circuit current, can become effective. My invention is further novel by providing a distance of engagement of the arcing contact, that varies in accordance with the current flowing in the system, which variation in distance is directly responsive to the amount of current present at the arcing contacts.

While I have shown a single embodiment of my invention, I do not wish to be limited to this specific structure, as my invention may be employed in airbreak circuit interrupters as well as in oil-break circuit interrupters, and applied to either the main contacts or to arcing contacts, as herein shown. It is also feasible to have both pairs of arcing contacts constructed as is the one here described. I, therefore, do not wish my invention to be limited except as limitations may be imposed by the prior art.

I claim as my invention:

1. The combination with a main contact for a circuit interrupter having an arcing contact associated therewith, of a spring for retaining the arcing contact in a neutral position beyond the main contact when said members are in open circuit position, and a current path so associated with the arcing contact that said contact is biased beyond its neutral position when the circuit interrupter is being actuated to open position.

2. In a circuit interrupter having a plurality of separable pairs of main contact members, of a pair of arcing contact members associated with each pair of main contact members, one arcing contact member of each pair being flexibly mounted, springs for retaining the last said contact members

in a neutral position in advance of the main contact members when said members are separated, and a current-affecting loop associated with the flexibly mounted contact members that are forced beyond their neutral positions when the current has been shifted thereto after the main contact members have separated. 70

3. In a circuit interrupter having a plurality of separable pairs of main contact members, of a pair of arcing contact members flexibly associated with each pair of main contact members, a spring on each contact member for retaining it in a neutral position in advance of the main contact members, when said members are separated and a current-affected loop associated with each of the contact members which forces the said contact members beyond their neutral positions when the current has been shifted to said loop after the main contacts have separated. 80

4. The combination with a pair of stationary contact members and a bridging member therefor, of an arcing tip connected to each of the said contact members, a pair of cooperating arcing tips associated with the bridging member and a current-actuating conducting loop associated with the first said arcing tips for providing a downward force to cause them to follow the arcing tips on the bridging members when current is flowing in the loop after the main contacts are separated. 90

5. The combination with a pair of stationary contact members and a bridging member therefor, of an arcing tip connected to each of the said contact members, a pair of cooperating arcing tips associated with the bridging member, biasing means on the first said arcing tips adapted to retain them in a neutral position in advance of the stationary contact members when said contact members are separated, and means associated with the first said arcing tips adapted to provide a magnetic repellent force that actuates them downwardly against the force of the said neutralizing biasing means to provide a larger separation of the bridging member from the contact members before 105 the arcing tips become disengaged, than the separation thereof when the arcing tips become engaged during the closing movement. 110

6. The combination with two relatively movable main contact members, of an arcing contact member associated therewith and flexibly connected to one of the said main contact members, a spring for retaining the arcing contact member in a neutral position 120 in advance of the main contact member, when said contact members are separated, and a U-shaped flexible conductor forming a current path to the arcing contact member for moving it downwardly beyond said 125 130

- neutral position when current is flowing through said U-shaped conductor.
7. A contact for a circuit interrupter characterized by the association of a substantially U-shaped current path and a neutralizing spring whereby the contact will be effective through a greater distance in the opening than in the closing movement of the circuit interrupter.
- 10 8. The combination, in a circuit interrupter having main separable contact members, of auxiliary contact members associated therewith, a current-carry loop and a biasing means associated with the auxiliary contact members for causing the auxiliary contact members to be in engagement over a greater distance during the opening than during the closing movement of the main contact members.
- 15 9. The combination with cooperating contact members of a circuit interrupter, of a current path associated therewith for providing a movement to one of the contact members to retain it in engagement with its cooperating moving contact member through a distance that is proportional to the amount of current flowing through said current path.
- 20 10. A plurality of contacts for a circuit interrupter characterized by the association of a substantially U-shaped current path and a neutralizing spring with each contact whereby the contacts will be effective through a greater distance in the opening than in the closing movement of the circuit interrupter.

In testimony whereof, I have hereunto subscribed my name this 26th day of October, 1928.

JOHN B. MACNEILL.
